[57] CLAIM

The ornamental design for the mobile storage apparatus, as herein shown and described.

DESCRIPTION

FIG. 1 is a perspective view of the mobile storage apparatus constructed according to the present invention with the lid thereof in a closed position;

FIG. 2 is a front elevational view of the invention illustrated in FIG. 1;

FIG. 3 is a rear elevational view of the invention illustrated in FIGS. 1 and 2;

FIG. 4 is a top view of the invention illustrated in FIGS. 1-3;

FIG. 5 is a bottom view of the invention illustrated in FIGS. 1-4;

FIG. 6 is a left side elevational view of the invention illustrated in FIGS. 1-5;

FIG. 7 is a right side elevational view of the invention illustrated in FIGS. 1-6;

FIG. 8 is a perspective view of the mobile storage apparatus constructed according to the present invention with the lid thereof in an open position;

FIG. 9 is a front elevational view of the invention illustrated in FIG. 8;

FIG. 10 is a rear elevational view of the invention illustrated in FIGS. 8 and 9;

FIG. 11 is a top view of the invention illustrated in FIGS. 8-10;

FIG. 12 is a bottom view of the invention illustrated in FIGS. 8-11;

FIG. 13 is a left side elevational view of the invention illustrated in FIGS. 8-12; and,

FIG. 14 is a right side elevational view of the invention illustrated in FIGS. 8-13.
